DIE SUSPENSION

Roy M. Hukle, Muskegon, Mich., assignor to
Anaconda Wire & Cable Company, a corpora-
tion of Delaware

Application December 27, 1939, Serial No. 311,123

8 Claims. (Cl. 91—53)

This invention relates to coating articles such as wire with varnish or like plastic or viscous fluid substances, and has for its principal object the provision of an improved apparatus and method for applying such coatings.

In the customary method for coating wire with thin liquid enamels and the like, the wire is drawn off a feed reel through a bath of the liquid coating material, and thence is passed through a heating chamber or oven where the coating material adhering to the wire is baked on. The finished product is drawn from the oven and wound on a suitable reel. This method is satisfactory so long as the coating material is of such non-viscous character that a thin coating of uniform thickness adheres to the wire as a result of its being drawn through the bath of coating material. However, in an effort to provide improved coating materials, thick, heavy varnishes, such as polyvinyl acetal varnishes, have been developed. These are of such viscous character that it is not possible to obtain a thin coating of uniform thickness simply by passing the wire through the coating material, for such materials adhere to the wire in the form of heavy coats of irregular thickness. In order to form a thin uniform coating, it has been proposed to draw the wire, after passage in contact with the viscous coating material, through a die to remove excess coating material and produce a film of uniform thickness about the wire. This proposal has been difficult to carry out successfully because of the difficulty of keeping the wire centered in the die. There is a tendency for the wire to whip somewhat as it passes rapidly through the die, and the irregular lateral movement resulting from this whip makes it virtually impossible to keep the wire properly centered in the die. Unless the wire is properly centered, the coating produced is not of uniform thickness, for if the wire whips to the side, too much coating material is taken off that side and not enough off the other.

The present invention overcomes this difficulty by providing an improved apparatus in which the die is suspended or "floated" so that it may be free to move to a limited extent in all directions. The die thus is enabled to center itself about the wire, with the result that a coating of uniform thickness is formed on the wire.

In accordance with the invention, a die comprising magnetizable material is disposed within a magnetic field in such manner that the die is free to move to a limited extent in all directions within the field, but the field is made sufficiently

strong to prevent withdrawal of the die therefrom by forces normally acting on the die. In a preferred embodiment of the invention, a die chamber is formed within the field of an electromagnet. A die of magnetizable material is positioned within the die chamber in such manner as to be free to move to a limited extent in all directions. Means are provided for drawing a wire through the die, and other means are provided for energizing the electromagnet sufficiently to create a strong enough magnetic field to prevent withdrawal of the die from the die chamber either by the force of gravity or by forces acting on the die as wire is drawn therethrough.

15 The apparatus of the invention may be arranged to permit wire to be drawn either vertically or horizontally through the die. In the former case, the die may be positioned within a simple annular electromagnet coil or solenoid. In the latter case, it is preferred to employ upper and lower electromagnet coils with the die chamber and die located in the field between them, provision being made to energize the upper electromagnet coil with a greater number of ampere-turns so as to balance the force of gravity tending to pull the die downwards.

20 The invention will be better understood from the following description, considered in conjunction with the accompanying drawing, in which

25 Fig. 1 is a schematic elevation of a wire coating apparatus including the apparatus of the invention;

30 Fig. 2 is a cross-section through the magnetic die suspension apparatus shown in Fig. 1; and

35 Fig. 3 is an elevation of modified die suspension apparatus especially adapted for drawing wire horizontally.

36 The apparatus shown in the drawing (Fig. 1) comprises a supply reel 10 from which wire 11 to be coated is drawn. The wire passes over a guide sheave 12 through a gland 13 in a vessel 14 containing a viscous varnish, such as a solution of polyvinyl formal or other polyvinyl acetal composition. The wire passing through the vessel 14 acquires a heavy, irregular coat of the viscous varnish.

40 In order to remove excess varnish adhering to the wire and to produce a uniform varnish film thereabout, the coated wire from the varnish vessel is passed through a die 15 comprising magnetizable material disposed in a die chamber within the field of an annular electromagnet or solenoid coil 16. The electromagnet coil is energized sufficiently by a generator G to produce a field sufficiently strong to prevent withdrawal of the die from the die chamber by

the force of gravity or by the force exerted on the die by the wire being drawn therethrough. The die, however, is free to move to a limited extent in all directions within the die chamber, and so is able to accommodate irregular lateral motion of the wire and remain centered at all times about the wire. Consequently the varnish film about the wire emerging from the die is substantially uniform in thickness around the circumference of the wire.

The wire emerging from the die passes through an oven 17 of conventional design, in which the varnish is baked on the wire at temperatures suitable for the particular coating composition employed, and thence over a guide sheave 18 to a take-up spool 19.

An enlarged cross-section through the electromagnet and die is shown in Fig. 2. The wire 11 with its thick, irregular coating of varnish 20 passes substantially vertically upwards through the die 15. The die aperture 21 through which the wire passes is of a diameter equal to that of the wire plus twice the thickness of coating desired. The entrance 22 to the die aperture, which faces the vessel 14 containing the coating material, is flared outwardly to form a bell-shaped mouth, thus providing for smooth admission of the wire to the die aperture. The bell-shaped entrance 22 also allows the excess varnish being scraped from the wire to build up enough pressure to aid in keeping the die centered about the wire.

The die 15 comprises a large proportion of iron or other magnetizable material, and is positioned within a die chamber 23 defined by the cylindrical opening through an electromagnet coil or solenoid 16. The wire passes substantially centrally through this die chamber. The die, which advantageously is generally spherical in shape (it may be made, for example, from a steel ball bearing), is considerably smaller in diameter than the die chamber 23, and so is free to move to a limited extent (determined by the bounds of the die chamber) in any direction.

The electromagnet coil 16 is composed of a sufficient number of turns of wire, and is energized sufficiently from a suitable source of current, to create a magnetic field in and about the die chamber and the die therein which is strong enough to prevent withdrawal of the die from the die chamber either by the force of gravity or by the force exerted on the die by the wire being drawn therethrough. So long as the die remains within the die chamber, it is free to move in any direction, but as soon as the die begins to emerge from the chamber, the magnetic forces developed by the energized coil resist further withdrawal. Hence the die is enabled to move with sufficient freedom in any direction to accommodate irregular lateral movement of the wire being drawn therethrough, and yet is held by magnetic forces within the confines of the die chamber.

The die 15 is shown in Fig. 2 substantially as it appears when a wire is being drawn therethrough with the electromagnet coil properly energized. The drag of the wire has drawn the die to the upper limit of the die chamber, but this force tending to withdraw the wire from the die chamber is more than balanced by the magnetic forces developed by the electromagnet coil. The die, therefore, is prevented from being wholly withdrawn from the die chamber, but it is free to move laterally to a limited extent to accommodate irregular lateral motion of the wire.

The electromagnet coil 16 shown in the drawings is of conventional solenoid construction. It comprises a large number of turns of wire of suitable size wound on a cylindrical form 24, which 5 form defines the boundaries of the die chamber 23. Annular end plates 25 serve to retain the coil on the cylindrical form. The form 24 should be of brass, copper, plastic composition, or other suitable non-magnetic material so as not to short-circuit the magnetic flux path through the die chamber. The annular end plates 25, however, may be of iron, and the cylindrical outer surface of the coil may be surrounded with iron or other suitable magnetic material so as to improve the flux path throughout this portion of the magnetic circuit, and thus increase the magnetic efficiency of the structure.

The terminals 26 of the coil are connected to a suitable source of current for energizing purposes. Any of the usual sources of either alternating or direct current may be employed. The voltage impressed across the terminals 26 of the coil 16 depends at least in part upon the electrical design of the coil, and any alternating or direct current source capable of supplying this voltage, such, for example, as alternating or direct current generators, or batteries may be used:

The particular construction and shape of the electromagnet structure described above and shown in Fig. 2 is generally satisfactory, but the invention is not limited to any particular form or shape of electromagnet structure. For example, in some cases it may be preferred to form the die chamber, and correspondingly the form 30 on which the electromagnet coil is wound, with a central portion of reduced diameter and ends of greater diameter, thus providing a form in the shape of the well-known hour glass. Instead of circular forms on which the coil is wound, square or rectangular forms may be employed if desired. It is even possible to employ permanent magnets instead of electromagnets about the form to provide the magnetic field required to hold the die within the die chamber.

The electromagnet structure described above is particularly suitable for use in cases where a wire is drawn vertically, or at an inclination approaching the vertical, through the die. In cases where it is desired to draw a wire through the die horizontally or at an inclination approaching the horizontal, a modified form of electromagnet structure generally is preferred. Such a structure is shown in Fig. 3. In this modified apparatus a spherical die 30, preferably constructed similarly to the die 15 described above, is mounted so as to be free to move to a limited extent in any direction within the confines of a die chamber 31. The die chamber 31 is defined by a pair of form members 32 of substantially semi-cylindrical shape. Arcuate sections 33 are cut from the edges of the form members 32 near the central portion thereof. Upper and lower electromagnet coils 34 and 35 are wound on the forms 32 above and below the arcuate cut-out portions 33, and the terminals 36 and 37 of these coils are connected to a suitable source of alternating or direct current.

In order to compensate for the effect of gravity tending to pull the magnetizable die 30 downwardly, provision is made for energizing the upper magnet coil 34 to a sufficiently greater extent than the lower coil 35 to balance magnetically this effect of gravity on the die. This may be done in the case of electromagnet coils by providing for energizing the upper coil 34 with a

greater number of ampere-turns than the lower coil. The upper coil 34 thus may be wound with a larger number of turns than the lower coil 35 and both coils may be energized with current of the same ampere value, or both coils may be wound with substantially the same number of turns, and a current of greater ampere value may be passed through the upper coil 34 than through the lower coil. The coils may be connected in a series or in parallel, as desired.

Operation of the modified electromagnet structure is substantially the same as that described above in connection with the apparatus shown in Fig. 2. Wire to which a relatively heavy irregular coat of varnish has been applied is drawn substantially horizontally, or inclined somewhat with respect to the horizontal, through the die. The force exerted on the die by the wire passing therethrough and tending to withdraw the die from the die chamber 31 is resisted and overcome by the magnetic forces acting on the die to retain it within the die chamber. The die, however, is free to move laterally to a limited extent in any direction to accommodate irregular lateral motion of the wire and so to remain centered about the wire.

I claim:

1. Apparatus of the character described comprising a die chamber, a die of magnetizable material positioned within said chamber so as to be free to move in any direction within the confines thereof, means for drawing a wire horizontally through said chamber and through the die, electromagnet coils mounted above and below the die chamber in magnetic relation with the die therein, and means for energizing said coils sufficiently to create a magnetic field in and about said die chamber of sufficient strength to prevent withdrawal of the die from the chamber by the forces exerted on the die as wire is drawn therethrough.

2. Apparatus of the character described comprising a die chamber, a die of magnetizable material positioned within said chamber so as to be free to move in any direction within the confines thereof, means for drawing a wire horizontally through said chamber and through the die, a first electromagnet coil mounted above said die chamber in magnetic relation with the die therein, a second electromagnet coil mounted below said die chamber in magnetic relation with the die therein, and means for energizing said coils sufficiently to create a magnetic field in and about said die chamber of sufficient strength to prevent withdrawal of the die from the chamber by the forces acting on the die as wire is drawn therethrough, said first electromagnet coil being energized with a sufficiently greater number of ampere-turns than said second electromagnet coil so as approximately to balance the downward pull of gravity on the die.

3. Apparatus of the character described comprising means for creating a magnetic field, a die of magnetizable material having a die opening extending therethrough positioned in said magnetic field, said magnetic field being sufficiently strong to prevent withdrawal of the die therefrom by forces normally acting on the die, means for drawing a wire having coating composition thereon through the die opening, the entrance portion of said die opening being flared in a manner to maintain the die at all times centered about the wire, and the die being free to move to a limited extent in all directions within the magnetic field to accommodate irregular

lateral movement of the die as the wire is drawn therethrough.

4. Apparatus for coating wire with a plastic composition comprising means for applying said composition to a wire, and means for removing excess composition from the wire and forming a uniform film thereof about the wire comprising a magnet, a die of magnetizable material having a die opening extending therethrough positioned in the field of said magnet, said field being sufficiently strong to prevent withdrawal of the die therefrom by forces normally acting on the die, means for drawing the composition-coated wire through the die opening, the entrance portion of said die opening being flared in a manner to maintain the die at all times centered about the wire, and the die being free to move to a limited extent in all directions within the magnetic field to accommodate irregular lateral movement of the die as the wire is drawn therethrough.

5. Apparatus of the character described comprising an electromagnet, a die chamber arranged within the field of said electromagnet, a die of magnetizable material having a die opening extending therethrough positioned within said die chamber, means for drawing a wire having coating composition thereon through the die opening, the entrance portion of said die opening being flared in a manner to maintain a die at all times centered about the wire, and means for energizing the electromagnet sufficiently to prevent withdrawal of the die from the chamber by the forces exerted on the die as the wire is drawn therethrough, the die being free to move to a limited extent in all directions within the die chamber to accommodate irregular lateral movement of the die as the wire is drawn therethrough.

6. Apparatus of the character described comprising an annular electromagnet coil, a die of magnetizable material having a die opening extending therethrough positioned within said coil, means for drawing a wire having coating composition thereon vertically through said coil and through the opening of the die therein, the entrance portion of said die opening being flared in a manner to maintain the die at all times centered about the wire, and means for energizing the coil sufficiently to create a magnetic field of sufficient strength to prevent withdrawal of the die from its position in the coil by the force of gravity or by the force exerted on the die as the wire is drawn therethrough, the die being free to move to a limited extent in all directions within the electromagnet coil to accommodate irregular lateral movement of the die as wire is drawn therethrough.

7. Apparatus of the character described comprising a die chamber, a die of magnetizable material having a die opening extending therethrough positioned in said die chamber, means for drawing a wire having coating composition thereon horizontally through said chamber and through the opening of the die therein, the entrance portion of said die opening being flared in a manner to maintain the die at all times centered about the wire, the die being free to move to a limited extent in all directions within the die chamber to accommodate irregular lateral movement of the die as the wire is drawn therethrough, electromagnet coils mounted above and below the die chamber in magnetic relation with the die therein, and means for energizing said coils sufficiently to create a magnetic field in

and about said die chamber to prevent withdrawal of the die from the chamber by the forces exerted on the die as wire is drawn therethrough.

8. The method of coating a wire with a film of uniform thickness of a viscous liquid which comprises applying a relatively thick coating of the liquid to a wire, passing the thus-coated wire through a die of magnetizable material, whereby excess liquid is removed from the wire, and creating a magnetic field about the die in such man-

5
10
ner as to establish about the die a magnetic field substantially balanced radially about the wire thus permitting the die to move freely to a limited extent in any direction radially about the wire, said balanced field being of sufficient strength to prevent withdrawal of the die out of said balanced magnetic field by the forces acting longitudinally of the wire as the wire is drawn through the die.
